CLAIM

The ornamental design for a drink machine, as shown and described.

DESCRIPTION

FIG. 1 is a perspective view of a drink machine showing my new design;

FIG. 2 is a front view of the design shown in FIG. 1;

FIG. 3 is a back view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1; and,

FIG. 7 is a bottom view of the design shown in FIG. 1.

The broken lines shown in the drawings represent unclaimed portions of the drink machine and form no part of the claimed design.
